Fig. 2.

UNITED STATES PATENT OFFICE

CARL G. FISHER, OF MONTAUK, NEW YORK

LIFEBOAT

Application filed August 24, 1929. Serial No. 388,152.

This invention relates to life boats and particularly to distress signal apparatus to be used in connection with the life boats. An object of the invention is to provide a new 5 and improved life boat or life raft and means for displaying a distress signal on the boat so that it may be seen from a great distance.

A further object is to provide a new signalling device and a new method of mounting 10 and operating the same.

Further objects will become apparent as the description proceeds.

Referring to the accompanying drawings which are made a part hereof and on which 15 similar reference characters indicate similar parts,

Figure 1 is a view of a life boat having my signalling apparatus attached thereto,

Figure 2 is a view of the signalling balloon 20 showing the lighting apparatus mounted thereon.

In the drawings numeral 10 indicates a life boat having air chambers 11 and 12 at each 25 end or otherwise positioned on the boat in order to keep it buoyant even though it might be capsized.

The boat itself is constructed of strong light material. For example the ribs 13 may be made of metal or wood frames or of rubber 30 frames, whale bone or other strong but somewhat resilient material. To these ribs the body of the boat is sewed or riveted so as to make a rugged construction but yet relatively light.

35 A storage cabinet 14 is secured within the boat in which cabinet signalling apparatus is kept when the boat is not in use as a life boat. Mounted at a suitable place on the boat is a reel or windlass 15 to which a cable 16 is secured and around which it is wound when the boat is not in use. The cable 16 secures a balloon 17 having a suitable signal light 18 mounted above it. The cable 16, of course, may be of any convenient length so as to allow the balloon with its signal light to be seen from a 45 great distance. A balloon of convenient size may carry a cord as much as 300 feet long. A cable of this length allows the balloon to rise to a height at which it may be seen from a very great distance. The balloon and the

means for mounting and operating the light will now be described. The balloon itself may be made of any suitable material such for example as a light high quality of silk reinforced by very light netting in order to reinforce the bag to withstand the pressure of the gas which is somewhat higher than that normally required in balloons for a reason which will later appear.

The lower part of the balloon bag is secured around a tube 19 which projects into the bag. This tube 19 has a bottle or drum 20 on its lower end which drum is filled with hydrogen gas under a relatively high pressure. For a small balloon of the kind contemplated a drum containing between eight to ten cubic inches is sufficient. These are filled with hydrogen gas to a pressure of from 400 to 600 pounds per square inch. The drum itself may be made of thin high tensile steel or out of duraluminum. The tube 19 has a valve 21 by means of which the flow of gas from the drum 20 into the balloon may be regulated as desired. It may furthermore be desired to have the valve 21 automatic in action so as to keep a constant predetermined pressure within the balloon 17. Such pressure regulated valves are well known and since these form no specific part of the invention the details will not be further described.

The lighting apparatus is mounted on top of the balloon and is as follows: The top of the balloon is secured around a board or plate 22. This board may be of cork or other strong but light material. A plate of asbestos 34 is secured upon the cork board. A series of posts 23 of strong light material such for example as aluminum wires may form a frame work for supporting mica plates 24 to form a housing for the light. A cover of mica plates or other suitable material may be provided with ventilating openings 25. Openings 26 at the base of the housing provide suitable air inlets for a gas burner 27 upon which a suitable mantle 28 is supported. The gas mantle is supported by wires 29. A reflector 30 is secured beneath the burner. This reflector may be of any suitable material such for example as polished chromium. The burner tube 27 extends through the plate 22

into the gas bag and has an adjustable needle valve 31 to control passage of gas from the balloon to the burner. A suitable catalytic agent 32 may be secured adjacent the mantle 5 29 which agent provides automatic means for lighting the burner when the gas is turned on, such agents being well-known will not be further described.

By constructing the lamp of light strong 10 materials the weight of the balloon, the lamp and the gas drum combined may be relatively small so that a balloon bag having a capacity of approximately 30 cubic feet will be sufficient to support the light. Additional drums 15 20 may be stored in the cabinet in the boat. A gas drum of the size mentioned with pressures from 350 to 500 pounds per square inch are thought sufficient to maintain the balloon aloft and the light burning for approximately 20 24 hours. At the end of this time the balloon may be drawn down and the drum 20 unscrewed from the stem 19 and a fresh drum attached to it, the valve 21 of course being closed to maintain the supply of gas within 25 the balloon.

The operation of the device should be apparent from the description. When the life boat has been launched a balloon 17 is attached to a gas tank 20 which tank has an eye 30 in its lower end to which the cable 16 is attached. Valves 31 and 21 are adjusted so that gas may escape from the drum 20 into the balloon bag, and may be fed through the valve 21 into the burner to maintain the light. 35 The balloon is then allowed to ascend by allowing windlass 15 to unwind. A suitable distress signal 33 such as an inverted American flag may be attached to the cord 16 beneath the balloon. The flag serving as a signal during the daytime and after the supplies 40 of hydrogen gas have been exhausted until only enough remains to keep the balloon aloft.

Under certain circumstances I may find it desirable to use an electric light instead of the 45 lamp and operate it from dry cell batteries suspended beneath the balloon or kept in the boat. When kept in the boat the cable 16 may be a suitable conducting cable.

While I have shown the gas burner as being supplied with gas from the interior of the balloon bag, under certain conditions I may find it preferable to supply gas direct from the gas drum to the light by connecting a tube from the gas drum to the burner. It may even 55 be desirable under some conditions, as for example with certain sizes of life boats to carry the supply of fuel gas for the light in drums in the life boat and supply the gas to the burners by long tubes. These and other modifications are deemed to be within the scope of my invention.

It will be obvious to those skilled in the art 60 that various further modifications and changes may be made in my device without departing from the spirit of the invention

and therefore I do not limit myself to what is shown in the drawings and described in the specification, but only as indicated in the appended claims.

While I have described this invention as relating to "life boats" it will be understood, of course, that by such term I include airplanes and all craft for which the invention may appropriately be adapted, whether on the sea, in the air, or on the land.

Having thus fully described my said invention, what I claim as new and desire to secure by Letters Patent, is:

1. A life boat having buoyant means associated therewith, a container for signalling apparatus, a balloon adapted to be attached to, to rise above the boat and having signalling devices supported thereby, and a drum detachably suspended from the balloon having means for gradually supplying gas to the balloon to compensate for gas escaping from the balloon, substantially as set forth. 80

2. A life boat having signalling apparatus mounted thereon, the said signalling apparatus comprising a balloon, a gas burner mounted upon the balloon, a gas drum suspended from the balloon, means for permitting gas to be fed from the drum to the balloon, and means for permitting gas to be fed from the balloon to the burner to maintain a signalling light, substantially as set forth. 90

3. A signalling apparatus for a life boat comprising a balloon anchored to the boat, means for raising and lowering the balloon, a gas drum mounted below the balloon, means for supplying gas from the drum to the balloon, a plate mounted upon the balloon, a transparent housing mounted upon the plate, a gas burner within the housing, means for supplying gas from the balloon to the burner, and means for adjusting the rate of flow of the gas from the balloon to the burner and from the drum to the balloon to maintain a predetermined pressure within the balloon, and a predetermined supply of gas to the burner, substantially as set forth. 100

4. A signalling apparatus for a life boat comprising a balloon anchored to the boat, means for raising and lowering the balloon, 115

a gas drum mounted below the balloon, means for supplying gas from the drum to the balloon, a plate mounted upon the balloon, a transparent housing mounted upon the plate, a gas burner within the housing, means for supplying gas from the balloon to the burner, means for adjusting the rate of flow of the gas from the balloon to the burner and from the drum to the balloon to maintain a predetermined pressure within the balloon, and a predetermined supply of gas to the burner, substantially as set forth. 120

5. A life boat having gas compartments 130

built into each end to provide buoyancy for the boat, a reel rotatably secured at one end of the boat, a storage chamber for signalling apparatus positioned adjacent the said reel, 5 a cable wound around the reel having a balloon attached to one end, a gas drum detachably secured to the lower end of the balloon to supply it with gas and a signal light mounted upon the balloon, and means for 10 controlling admission of gas from the drum to the balloon to maintain the balloon inflated, substantially as set forth.

6. A signal device for a life boat comprising a balloon attached to rise above the life 15 boat, means for maintaining a predetermined gas pressure within the balloon to maintain it aloft, a signal light carried by the balloon, and means for maintaining the light by escap- 20 ing gas from the balloon, substantially as set forth.

7. A signalling apparatus for a life boat comprising a balloon anchored to the boat, a gas drum mounted below the balloon, means for inflating said balloon from said gas 25 drum to cause it to rise, a plate mounted in the top of said balloon, a transparent hous- 30 ing mounted upon the plate, a gas burner within the housing, means for supplying gas to said burner from the inflated balloon, 35 means for maintaining a predetermined pressure in said balloon by regulating the rate of flow of the gas from said tank to said balloon, means for maintaining a pre- determined supply of gas from said balloon to said burner, and means incorporated in 40 said burner for automatically lighting the same when the gas is supplied thereto, sub- stantially as set forth.

In witness whereof, I have hereunto set 45 my hand at Montauk, Long Island, New York, this 23rd day of August, A. D. nineteen hundred and twenty-nine.

CARL G. FISHER.
